J. M. WILLBUR, OF CLEVELAND, OHIO.

Letters Patent No. 82,464, dated September 22, 1868; antedated September 17, 1868.

IMPROVED STEREOTYERS' PUTTY.

The Schedule referred to in these Letters Patent and making part of the same.

To all whom it may concern:

Be it known that I, J. M. WILLBUR, of Cleveland, county of Cuyahoga, in the State of Ohio, have invented a new and improved Stereotypers' Putty; and I do hereby declare that the following is a full and exact description thereof.

The nature of this improvement relates to the composition of a substance to be used as a filling to be put between the letters or type, when the types are set up in form, to make a smooth, even surface before the mould is taken from the type, and which may be readily washed down with a brush to any required depth, leaving the type perfectly free and clean, ready for receiving the plaster for taking the mould. It may also be removed readily, and be used over again repeatedly, as it is not necessary to have it dry in place about the type, before taking the plaster mould. It may also be used for taking impressions of seals or stamps, for the purpose of duplicating them. It takes a very smooth, perfect impression, and draws freely from the pattern. By this means notarial, society, and other seals may be very readily and perfectly reproduced by electrotyping or stereotyping.

Plaster of Paris has been used heretofore as a filling to level up the surface around the type for stereotyping, but it is very difficult to remove it from near the face of the type, as it sticks and dries upon them,

and has to be picked off with a graver or bodkin, which is a slow, tedious job.

This putty is composed of potters' clay and olive-oil, (linseed-oil may be used instead, but it causes the putty to dry up sooner,) which, having no affinity for water, or for the type or patterns in connection with which it is used, renders it easily separated from them in the process of taking moulds or casts; it, therefore, renders the operation of stereotypers more easily and perfectly performed, saving much time and labor. It may also be made and packed in bladders for sale, similar to glaziers' putty. It may also be renewed by adding a little oil and working it in, if at any time it should become dried.

The mode of compounding this putty is as follows:

Take finely-ground potters' clay, which must be perfectly dry and free from grit, and add a sufficient quantity of pure olive-oil to give a proper consistency. Mix well together until it has the appearance of common glaziers' putty, when it is ready for use.

I claim the composition hereinabove described, for the purposes specified.

J. M. WILLBUR.
